COMBINED TABLE AND BENCHES

Ira D. Oglesby, Fort Smith, Ark., assignor to Ft. Smith
Plywood Company, Fort Smith, Ark.

Application November 14, 1955, Serial No. 38,875

Term of patent 3½ years

(Cl. D33—14)

Fig. 1 is a perspective view of a combined table and benches showing my new design; and

Fig. 2 is an end elevational view thereof.

The dominant features of the design reside in the portions shown in full lines.

I claim:

The ornamental design for a combined table and benches, as shown and described.
